UNITED STATES PATENT OFFICE.

WALTER TAYLOR ECROYD, OF MUNCY, PENNSYLVANIA.

AUTOMATIC TRAIN-CONTROL MECHANISM.

1,242,665.

Specification of Letters Patent.

Patented Oct. 9, 1917.

Application filed June 15, 1914. Serial No. 845,188.

To all whom it may concern:

Be it known that I, WALTER TAYLOR ECROYD, a citizen of the United States, and a resident of Muncy, county of Lycoming, 5 State of Pennsylvania, have invented certain new and useful Improvements in Automatic Train-Control Mechanism, of which the following is a full description.

The object of the invention is to provide a 10 device operative to so control the motive power of a steam or electric locomotive or train, and the pneumatic brake mechanism thereof, that the speed of said locomotive or train will be automatically reduced upon the 15 event of their being driven past a "caution" signal.

Another object of the device is to automatically apply the air to the brake mechanism in a manner exactly similar to that 20 employed by an experienced engineer in bringing a train to a partial or full stop.

To accomplish the first result, it is the object of the device upon passing a "caution" signal to shut off a portion of the steam pressure and simultaneously shift a valve, either 25 the same as, or similar to, the engineer's valve from "running" position, to "service" position, and thence to "lap" position.

To completely stop the train, upon passing 30 a "danger" signal, the steam is partially shut off and the valve, above mentioned, is shifted from "running" position to "service" position, thence to "lap" position. The steam is then completely shut off and the 35 said valve is shifted at predetermined intervals of time from "lap" position to "service" position, and thence to "holding" position, at which point the air brakes bring the train to a full, though gradual, stop and substantially without jarring.

Another object is to provide such a mechanism in conjunction with distinct audible signals, to designate the time and manner of operation of the device, *i. e.*, whether being 45 operated on the passing of a "caution" or a "danger" signal.

A further object is to provide damped disk motors for operating the various mechanisms, contact disks revolved thereby, and 50 means for adjusting the contacts on said disks, to predetermine the time of changing the positions of the brake valve.

In this connection, another object is to provide means for automatically stopping 55 the operation of said motors at a predetermined point and after a predetermined period of operation.

Other objects are to provide a simple means for indicating the dangerous spread of rails; to provide means for indicating an open switch; the breaking of any of the principal moving parts of the locomotive operating mechanism, etc.

A still further object is to provide an operating mechanism adapted to be carried by the locomotive, and an improved track member so positioned and shaped as to operate said mechanism, the latter, however, being shielded from any and all other objects which may be on or adjacent to the track.

Another object is to provide a selective locomotive contact member, the extent of the operation of which is varied depending upon the elevation of a track tripper device, in turn operated by and simultaneously with a neighboring semaphore, or other signal.

Various further objects of the invention are hereinafter fully brought out in the following specification, reference being had to the accompanying drawings, in which—Figure 1 is a general diagrammatic view of the locomotive steam and air operating circuits and mechanisms; Fig. 2 is an enlarged fragmentary detail view of a portion of a locomotive including the control operating track mechanisms; Fig. 3 is a detail view of the steam valve; Fig. 4 is a transverse view of the same; Fig. 5 is a side elevation of a locomotive to which the invention is applied; Fig. 6 is a diagrammatic view of the sliding contact; Fig. 7 is a wiring diagram showing the connection of the broken parts indicating device in the automatic train control circuit; Fig. 8 is a plan view of a section of track showing the application thereto of the improved "spread rail" indicating device; Fig. 9 is an enlarged detail section on the line 9—9 of Fig. 8; and Fig. 10 is a diagrammatic view showing the electric signal circuit and the manner of connecting the "spread rail" device therein.

In describing the construction and operation of this invention, reference is first made to Fig. 1 of the drawings, which gives a general idea of the various coöperating mechanisms. whereby in a given position of a semaphore arm the steam and air brake mechanism carried by a steam locomotive, or the electric current and air brake equipment on an electric locomotive or motor car is automatically operated.

The semaphore arm 20, shown at the base of the sheet as being mounted upon the usual post 21, is adapted to move upon the

pivot 22 into the positions A—"danger", B—"caution", and C—"clear", the movement of said arm oscillating in any suitable manner the shaft 23 and arm 24, on the latter of which is pivotally mounted a track tripper device 25, comprising a substantially triangular body portion 26 and lower weight portion 27, the latter being adapted to maintain the former in upright position, but permitting the device as a whole to rock substantially freely. Or, instead of the tripper being yieldingly maintained in a normal position by gravity alone, it may be suitably positioned by one or more resilient members attached thereto. As the semaphore arm 20 enters the respective positions A, B and C, the shaft 23 revolves, to place the axis of oscillation of the tripper at the respective elevations A', B' and C'.

Shown immediately above the tripper is a portion of a frame 25^a to which are secured downwardly converging guards or fenders 26^a, having parallel adjacent faces between which slides a member 27^a, preferably made of suitable insulating material and carrying contact members 28 and 28^a, said first member being operative to slide upwardly upon being struck by one of the points 29 of the tripper, as the projection 30 thereof is forced to one side upon being struck by one of the guards 26, as the locomotive so equipped passes thereby.

Also carried by the frame 25^a and in line with the upper end portion of the plunger 27^a are two pairs of contacts 35 and 36, pivotally mounted and yieldingly maintained in their lowermost positions by pairs of springs 37 and 38, respectively, provided with means for adjusting the tension placed upon them. In its lowermost position the tripper is easily cleared by the guards 26^a upon a moving locomotive; in the intermediate position one of said guards strikes the projection 30 and rocks the tripper so that the rear pointed portion 29 presses upwardly and forces the member 27^a into a position in which the metallic member 28^a bridges the gap between the contacts 35; and in its uppermost position the tripper is so rocked upon being struck by one of the guards that one of the points 29 forces the member 27^a upwardly until the gaps between both of the pairs of contacts 35 and 36 are bridged by the members 28 and 28^a, respectively, said contacts returning to their normal positions upon the release of the member 27^a by the tripper 25, or at a predetermined time thereafter.

Upon bridging the gap between the "caution" contacts 35, current from a source 40 energizes the electro-magnets 41, pulling downwardly upon the armature 42, and by virtue of the lever 43, forces the slotted link 44 upwardly, closing the knife-switch 45 and bridging the contacts 46 and 46^a, said

switch being maintained in closed position by the spring-pressed latch 47, and the link 44 returning to its lowermost position by virtue of the spring 48, as soon as the current is broken at the contacts 35.

The operation of the switch 45 closes an electric circuit from a source 49 through wires 49^a, 49^b, 49^c, a knife-switch 50, and a common type of damped disk motor 51, a motor provided with a disk revoluble between permanent magnets, which latter carries upon its shaft a contact disk 52, grounded through a source of current 53 by a wire 54 and revoluble in the direction of the arrow, said latter disk being provided with a main contact 55 and a secondary contact 56 out of circumferential alinement with one another, or located to engage the periphery and one side respectively of said disk. A buzzer 60 is shunted by wires 57 and 58 across wires 49^a and 49^b respectively, to sound during the operation of the motor 51. The motor 51 having been started is only stopped when the disk contact 56 and a spring contact 63 coöperate, energizing the coils 64, which pull the armature 65 downward and open the switch 50.

Said switch 50 is maintained in open position by a shoulder 66 on a spring-pressed latch 67. Just before the motor stops the contact 55 coöperates with a contact shoe 68 carried by a lever 69, which in turn carries an armature 70. Said coöperation completes a circuit through coils 75, which draw downwardly upon an armature 76 and close a knife-switch 77, normally maintained in open position by a lever 78 and spring 79, but when once closed, maintained so by a spring-pressed latch 80.

Switch 77 closes an electric circuit through a battery 81, wires 82 and 83 and coils 84 which latter pull upon an armature 85 and thus operate a lever 86, carrying a ratchet 87, adapted to operate a suitable recorder 88. Said lever also, through a link 89, bell 110 crank lever 90 and slotted lever 91, operates a lever 92 and valve disk 92' of a special form of valve 93, to partially stop the passage of steam therethrough. Simultaneously, a link 97 rocks a lever 98, normally positioned by a spring 99, said lever in turn operating a link 100, provided with a slot 101, receiving a pin 102 on the lever 103, preferably of an auxiliary air brake valve 104, said lever 103 assuming the position indicated by the line designated as "service".

The lever 86 also, by a slotted link 105, raises a knife-switch 106 to engage the contact 107 and, being held in that positon by a spring-pressed latch 108, the switch completes an electric circuit through wires 109 and 110, knife-switch 111, battery 112 and damped disk motor 113, the latter carrying upon its shaft a disk 115, provided with a projecting contact 117, normally in the

position shown in Fig. 1, but revoluble in a clockwise direction successively into the positions shown in the dotted lines. As the motor 113 revolves, the contact 117 engages the yielding contact 119, which may be set as desired circumferentially of said disk, and closes an electric circuit through the grounded battery, disk 115, contact 117, contact 119, wire 121 and grounded coils 122, which latter pull downwardly upon the armature 123 and operate a lever 124 and link 125, provided with a slot 126, engaging the pin 127 on the valve lever 103, to shift the latter to the position indicated by the line designated "lap", the first movement of said valve lever having raised the armature 123 from the coils 122.

After the disk has made a complete revolution, the contact 117 engages the spring-pressed contact shoe 128 and by the wire 128' energizes the magnet coils 129, drawing downwardly upon the armature 129' and automatically opening the switch 111 in the motor 113 circuit, said last switch being maintained open by the spring-pressed latch 111'.

If the semaphore is set at "caution" as the locomotive and train pass the same, the operation as above described, takes place, and upon the completion thereof the individual parts remain in the respective positions indicated, a decreased amount of steam still passing to the cylinders, while the air has been first applied at "service" to the 35 brakes on the locomotive, and then at "lap" to the brakes upon both the locomotive and any cars which it may be drawing. To reset the apparatus, either after a complete diminution of the speed has taken place or 40 after the attention of the engineer has been directed by the buzzer, that is, during the single revolution of the disk 52 and before the coöperation of the contacts 55 and 68, a suitable push button or spring-switch 130 is 45 provided and by suitable wires is connected to the coil 111', battery 131, coil 80', coil 67', coil 47', coil 131', coil 132', coil 108' and back to switch 130. These coils attract their respective armatures 111^a, 80, 67, 47, solenoid core 131^a, similar coil 132^a, and armature 108, and permit the attached springs to throw the respective switches into the respectively 50 opposite positions.

Magnets 131 and 132, also in circuit with 55 the switch 130 and battery 131, operate simultaneously, to open the steam valve 93, previously closed as hereinbefore described.

When a semaphore is set at "danger" and a locomotive is driven therewith, the tripper device being in the position A' as shown, the plunger 27^a is raised until the metallic cap 28^a bridges the gap between the contacts 36, while the sleeve 28 bridges the gap between the contacts 35. Although this 60 bridging of the gaps is but momentary, the

operating current is sufficiently strong to positively operate the magnet armatures, or the return of the plunger 27^a to its normal position may be retarded in any suitable manner.

One of the contacts 36 is grounded by the wire 135, while the other is connected by a wire 136, through a battery 137, to a pair of magnet coils 138, grounded at the other side. Thus, the full upward movement of the 75 plunger 27^a on energizing the coils 138, operates the armature 139 to rock the lever 140, which is maintained in the position shown by the spring-pressed latch 141. The rocking of the lever 140 on the pivot 142 actuates a link 142', to close a knife-switch 145, and also by a link 147, rocks the contact 148 upon a pivot 149 to the position shown, where it is adapted to coöperate with the contact 117 as the latter revolves. The 80 movement of the link 147, through the bell crank lever 150 and link 151, rocks a contact 152 upon a pivot 153 into the position shown. The switch 145 is connected by wires 155 and 156 to wires 49^a and 49^b for 85 a purpose hereinafter described.

The contacts 152 and 148, having been moved into positions shown, the disk contact 117, after leaving the contact 119, engages the former 152 and through a wire 95 160 operates the magnet coils 161, attracting the armature 162, which rocks the spring-set lever 163 by a sectional link 164, and by a link 166 provided with a slot 167, surrounding a pin 168 on the air valve lever 100 103, shifts the same from "lap" to "service" position. One section of the link 164 is provided with a slot 165, through which projects a pin 166' Fig. 4 on a lever 167', operating a valve disk 168' located within 105 the steam valve 93 and provided with an aperture 169. The movement of the lever 167' completes the closure of the steam passageway through said valve as begun by the movement of the lever 92 and disk 92', 110 said slot 167 permitting the return of the link 164 to normal position without moving the lever 167'.

The contact 117, continuing upon its course, encounters the contact 148, which 115 action operates a pair of magnet coils 173 through a wire 174, attracting the armature 175 (raised by the last previous movement of the lever 103), rocking the lever 176, link 177, lever 178, and link 179, the last being provided with a slot 180, through which a pin 181 on the valve lever 103 passes. The movement of these parts shifts said last-named lever from "service" to "holding" position, which eventually brings 125 the locomotive and train to a full stop.

There are certain times when on account of heavy traffic it is necessary to run consecutive trains so close that it is impossible to maintain an entire block between them. 130

1,242,665

In such cases, assuming that the engineer is acting under orders, there is provided a device for preventing either the partial setting of the air brakes on passing a "caution" signal, or the entire setting of the brakes on passing a "danger" signal. Such a device also permits an engineer to take his train cautiously past a signal set against him for the purpose of approaching close to a wreck, a disabled train, etc., or pass a signal known to be incorrectly positioned.

This device comprises the ordinary engineer's brake valve 185, handle or lever 186, and contact members comprising two insulated segments 187 and 188, with a suitable spring-pressed contact or "brush" 189 carried by said lever. When said lever is at "running" position, the "brush" 189 lies between said segments and to prevent the setting of the brakes on passing a "caution" signal, said lever is moved very slightly toward "holding" position indicated by line H, Fig. 1, but not far enough to change the combination of registering ports within the valve. By this movement, the "brush" contacts with the segment 187, causing a current from a battery 190 to pass through wires 192 and 193 to the magnet coils 195, and raise the armature 70, shifting the contact 68 out of the path of the moving contact 55, and thus preventing the operation of the magnets 75, 84, etc.

When as before stated, it is desirable to permit a train, possibly already running at a low rate of speed, to pass a "danger" signal, the lever 186 of the engineer's valve may be moved slightly toward "release" position indicated by the line R, Fig. 1, in which case the "brush" 189 contacts with the segment 188, causing an electric current to pass from a battery 196, through wires 197 and 198, and magnet coil 199, which attracts the spring-pressed latch or armature 141 and prevents the lever 140 from remaining in rocked position and setting the contacts 148 and 152, etc.

In the carrying out of this invention, provision has been made for detecting the breakage of any one of the principal parts 50 of the locomotive operating mechanism and the axles and wheels of the cars comprising the train. In Figs. 5, 6 and 7 are shown the location, construction and operation of the invention as applied to the locomotive, the exact details of construction not being essential, but the principle being as shown.

A lever 210 is pivoted at 211 to any adjacent stationary member, while a head 212, having a contacting surface 213, engages either frictionally or otherwise, one of the chief moving parts 214, under pressure of the tension spring 215, the pivot 211 and spring being preferably mounted upon a block 216, and this in turn being secured 65 against movement. A contact member 217

is adapted to vibrate freely between two contacts 218 and 219, according to any possible irregularities of the part 214, but said contacts are adjusted so that any breaking or fracture of the part in question will 70 move the lever 210 sufficiently to cause the contact member 217 to engage either one or the other of said stationary contacts.

This action causes a current from the battery 137 to pass through the wire 226, contacts, lever, wire 227, wire 135 to ground, energizing the coils 138 and actuating the armature 139 to close the switch 145, to start the motor 51 and the subsequent operation of the brake setting and steam closing 80 mechanisms, as hereinbefore described, when the device responds to the track tripper mechanism with a semaphore set at "danger," except that the magnets 41 and switch 45 are not operated. Instead, current 85 from the battery 137 operates the magnets 138 directly, closing the switch 145, which by means of the wires 155 and 156 starts the motor 51 by current from the battery 228, the shunted bell 229 ringing and apprising the engineer of the operation.

Figs. 8, 9, and 10 illustrate a provision for automatically operating the locomotive mechanism hereinbefore described, upon the approach of a train toward a block or section of track in which there occurs one or more instances of "spread rail" or contracted rail, the former existing when the distance between the rail centers becomes materially greater than the gage to which the track was set when originally laid, and the other case being that in which the distance between the rail centers becomes less than said gage.

In this part of the invention the track rail 230 is secured as usual in any suitable manner upon the upper surface of the ties 231, upon each side of said rails there also being secured at regular intervals plates 232, provided with upwardly projecting portions 233, terminating in diagonally upwardly extending portions 234, said latter portions overhanging the base of the rail 230 upon opposite sides thereof and extending to within a short distance of the web of 115 said rail. With this construction any lateral movement of the rail, either inwardly or outwardly for a distance even less than the breadth of the uppermost surface of the rail, causes a positive engagement of said web with one or more of said portions 234 upon one side thereof. Both the rail and the members 232 may be mounted upon sheets of insulating material 235 for the purpose of better insulating the same from the supporting ties, the spikes 236, which secure said members 232 in position, passing through apertures 237 in said members and being insulated therefrom by any suitable means 238.

Furthermore, and as a matter of protection, at least the portion 234 of the respective plates 232 is shielded by suitable insulating means 241. In the form shown said means comprises a canopy 241, which is secured to the tie or rail above the respective plates 232 and adapted to permit a contacting of said rail and plate portions therebeneath. With this construction, the accidental connecting of these two members by suitable metallic objects dropping from a train, etc., is prevented, and to a great degree the possibility of fraudulently connecting the same is greatly diminished.

15 A contacting of one of the rails with one of the plates 232 causes a current of electricity to pass from the battery 242, through said contacting members, and the relay coils 243, attracting the armature 244 and breaking the normally closed circuit from the battery 245 and through the signal operating mechanism 246. This signal is so positioned with respect to the dangerous section of track that a train will have sufficient time 25 and distance within which to be brought under complete control before approaching the affected portion of the track. It is to be noted that the coöperation of the rail and contact plates can be so arranged as to set the tripper device in either "caution" or "danger" position, the latter being preferred.

By placing the "spread rail" contacts upon opposite sides of switch-points, it is possible to set a "danger" signal and indirectly the track tripper device at any predetermined distance therefrom. Or, it has been found entirely feasible to adjust the elevation of a track tripper mechanism at 40 any given distance away from a switch-point by means of any suitable rod 250, connected at its opposite ends to bell crank levers 251 and 252, operated by the switch lever 253, and operating said tripper mechanism, respectively.

This description completes the various details essential to the efficient operation of my improved train control mechanism, and it is to be noted that I do not confine myself 50 to many small and relatively unimportant details of construction, the invention residing broadly in a new method of controlling the steam and air applications on a locomotive and train, in a manner as nearly as possible identical with that employed by an experienced engineer in bringing his train either to a partial or full stop. Certain parts may be incased as desired, to prevent any fraudulent operation of the mechanism, 55 or change in the setting of the same, by any of the train crew. Also in practice it has

been found that in most of the instances shown on the drawings it is preferable to employ solenoids, instead of the electric magnets.

65

What I claim and desire to protect by Letters Patent of the United States is:

1. An automatic train control mechanism, comprising an adjustable track member, a movable member carried by a locomotive 70 and actuated by the coöperation therewith of said track member, an electric circuit closed by said second member, a throttle valve, means controlled by said circuit operating on said valve to decrease the steam 75 pressure, a second electric circuit and a brake valve, said second circuit being included in said means and operating to actuate said second valve to apply the brakes.

2. An automatic train control mechanism, 80 comprising an adjustable track member, a movable member carried by the locomotive and actuated by the coöperation therewith of said track member, an electric circuit closed by said second member, a throttle 85 valve, means controlled by said circuit operating on said valve to decrease the steam pressure, a second electric circuit, and a brake valve, said second circuit being included in said means and operating to actuate said second valve to partly apply the 90 brakes, and said circuits being operative when the adjustable track member is in a different position to shut off all of the operating steam pressure and to fully apply 95 the brakes.

3. The combination with electric brake operating means mounted on a locomotive, said means including a circuit with a pair of spaced contacts, of a plunger carrying a 100 circuit closer adapted to engage said contacts but normally out of contact therewith, guards at opposite sides of the plunger, a rocker track member operated by said guards to actuate the plunger, and means 105 to adjust the position of said rocker member.

4. An automatic train control mechanism, comprising an air brake valve having a series of definitely arranged positions including intermediate positions between its 110 extreme positions, and electric means to shift the valve successively forward and backward from one to others of said positions through the entire series, as when said valve is manually operated.

In witness whereof, I have hereunto set my hand this eleventh day of May, A. D., 1914.

WALTER TAYLOR ECROYD.
